UNITED STATES PATENT OFFICE.

ELIZABETH M. SCHLOSSER, OF MINNEAPOLIS, MINNESOTA.

SANITARY BELT.

Application filed September 21, 1927. Serial No. 220,922.

This invention relates to a sanitary belt adapted to be worn around the waist of a woman during the menstrual period to support an absorbent pad adapted to collect and retain the excrements from the menstrual flow.

It is the object of this invention to provide such a belt having a pocket therein for carrying an extra absorbent pad in such a position that the extra pad will be unobservable through the wearing apparel of the woman wearing the belt.

This and other objects and advantages of the present invention will more fully appear from the following description made in connection with the accompanying drawings, wherein like reference characters refer to the same or similar various parts throughout, and in which,

20 Fig. 1 is a perspective view of the device, certain parts thereof being broken away to show the construction thereof, and

Fig. 2 is a vertical section of the device taken from front to rear thereof.

25 Referring to the drawings, a sanitary belt is provided having the front portion 3, the rear portion 4 and the wide elastic bands 5 extending between and connecting the respective right and left ends of the front and rear portions. The front portion 3 is formed from two strips of cloth 3^a of substantially triangular shape and the said strips are so placed that their edges are alined. The bottom and side edges of strips 3^a are secured 30 together by a tape 3^b, while the upper edges are secured together by the tape from the ends of the strips a short distance centrally to the points 6 and are unsecured between points 6 to form an open topped pocket 7, the said pocket being of wide, long and thin 35 shape. The tape 3^b is divided into two sections from the points 6 inwardly and the said sections are sewed or otherwise secured to the upper edges of the strips 3^a centrally from the points 6 to provide reinforced 40 upper edges. Half snap fasteners 8 are secured to the upper edges of the strips 3^a and are adapted when pressed together to co-operate with each other to close the upper edge 45 of the pocket 7. The rear portion 4 of the belt is formed from two strips of cloth 4^a corresponding to the strips 3^a but unlike strips 3^a the said strips 4^a are secured together along their bottom, end and top 50 edges by the reinforcing tape 4^b. The front and back portions 3 and 4, being of sub-

stantially triangular shape, are adapted to conform to the shape of the wearer's body when the belt is placed around the hips of the wearer. Secured between the pieces 3^a and pieces 4^a at the centers of the bottoms thereof are the short elastic strips 9, while secured to the lower ends of the strips 9 are the small cloth tabs 10 having reinforced edges. A pad of absorbent material 11 is 60 adapted to be secured to the tabs 10 as by means of safety pins 12 and to be held between the legs of the wearer against the vaginal cavity when the device is in use. The pocket 17 is of such size that a pad 13 65 similar to the pad 11 may be placed therein to be carried by the belt when the same is being worn. The pocket 7 is of such size as to just accommodate the pad 13 and the pocket being long, wide and thin will prevent the pad from bulging and thus being seen through the clothes of the wearer. The elastic bands 5, when the device is being worn, will act to prevent the pocket 7 from 70 becoming distorted in shape, due to resilient 75 tension of the bands against the entire width of the ends of the strips 3^a forming the pocket.

The device will be found to be very useful 80 in actual practice, inasmuch as an extra pad 85 can always be carried in the pocket 7 on the wearer's body and thus embarrassment and confusion will be obviated when it becomes necessary for the wearer to change pads.

It will, of course, be understood that various changes may be made in the form, details, arrangement and proportions of the various parts without departing from the scope of the present invention, which, generally stated, consists in the matter shown and described and set forth in the appended claims.

What is claimed is:

1. A sanitary belt adapted to fit about the waist of a wearer and having means at both front and rear thereof to which the ends of a pad of absorbent material are adapted to be secured, and also having a pocket formed in the front thereof within which an extra pad of absorbent material is adapted to be 100 carried.

2. A sanitary belt comprising a front portion composed of two sheets of material secured together along their bottoms and ends and open at their tops to form a pocket for 105 carrying a pad of absorbent material, means for releasably securing the top edges of said

sheets of material together, a back portion, bands extending between the ends of said front and back portions and tabs projecting downwardly from said front and back portions to which the ends of a pad of absorbent material are adapted to be secured.

3. A sanitary belt comprising a front portion composed of two sheets of material secured together along their bottoms and ends 10 to form a comparatively long, wide and narrow pocket for carrying a pad of absorbent material, means for releasably securing

the top edges of said sheets of material together, a back portion, wide resilient strips connecting the ends of said front and back portions and adapted to exert pressure evenly on the entire end surfaces of said sheets of material forming said pocket to retain the pocket in flat shape and tabs secured to said front and back portions to which the 15 ends of a pad of absorbent material are adapted to be secured.

In testimony whereof I affix my signature.

ELIZABETH M. SCHLOSSER.
